ABSTRACT

To permit random interconnection of two aligned, as well as angularly offset rail connections by means of a turntable having a straight connecting section and a curved connecting section, the curved connecting section is formed of two circular segments, curved in the same direction, and connected by a straight connecting segment, parallel to the straight connecting section.

TURNTABLE RAIL SWITCH FOR TRANSPORT SYSTEMS

The present invention relates to a turntable switch to connect the terminus of a track, or rail with other terminal ends of the track or rail, located in alignment with the first terminal end, or at an angle with respect thereto, to form a turntable switch, and more particularly to such a turntable switch for transport systems such as single-track suspended transport systems.

Switches to connect tracks, or rails by means of a turntable, selectively, are frequently so made that a rotary, disk-like element has a straight track, or rail, and a curved track or rail, the straight track connecting aligned track portions, and the curved rail connecting a rail portion with another one which is angularly offset therefrom.

It has previously been proposed to provide a turntable switch on which the ends of at least two track portions, joined together in a rotary assembly, are located on a circle concentric to the axis of the switch. One of the track portions forms part of a circular arc; the other is a straight line and a tangent to the arc, with the turntable axis as a center. The radius of the arc corresponds to the vertical distance between the tangent passing through the end points of the circular track portion, and the axis of rotation of the turntable or switch. This had the disadvantage that the ends of the track portions on the turntable do not terminate at a circle concentric with the axis of the rotary switch in radial direction, so that it is not possible to connect all track portions, respectively, with each other. Another, known, turntable switch utilizes two circular track portions and a straight connecting line. The turntable is controlled by a chain drive, in order to match the desired connecting track portions to the fixed track ends. The ends of the connecting tracks match radially with the fixed portion, by terminating at a circle concentric with the axis of rotation of the turntable. The size of this arrangement, however, does not correspond to the minimum size possible. It has also been proposed to form the track on a turntable by means of an S-shaped track and two straight connecting tracks. Such an arrangement does not, however, permit universal connection of any one fixed track with any other fixed track.

It is an object of the present invention to provide a turntable-type switch for use with tracked transport systems, such as single or double rail transports, or the like, which permits effective and flexible interconnection of tracks while being of small size.

SUBJECT MATTER OF THE PRESENT INVENTION

Briefly, a turntable-type switch has one straight connecting track and a pair of similarly curved circular segments, connected by a short straight track section, parallel to the straight connecting section extending across the turntable.

The invention will be described by way of example with reference to the accompanying drawings, wherein:

FIG. 1 is a schematic illustration of a turntable switch having a straight and a curved connecting section, in which the ends of the connecting sections are radial with respect to the center of the turntable; and

FIG. 2 is a fragmentary view of the turntable, to a larger scale, illustrating an arrangement for four equally distributed track ends, for universal connec-

tion, and in which the curved track segments are located in a circular segment having an angle, with respect to the center of the turntable, of 90°.

The basis for the present invention is the realization that the diameter of the turntable — as seen in FIG. 1 — can be solely determined by the minimum distance a between the straight track section 1 and the curved track section 2, considering the minimum radius of curvature of the curved connecting section 2. As seen in FIG. 1, the curved connecting section 2 includes a straight portion 3 of length b , which extends parallel to the straight connecting section 1. Two circular segmental portions 4, curving in the same direction, are joined to the straight portion 3. The radius of curvature of the curved segments 4 is r .

The turntable of the present invention is so constructed that the ends of the connecting sections 1, 2 terminate at the circumference of the turntable 5 in radial direction with respect to the center of the turntable. The outer track portions, which are fixed, are directed to fit against the circumference of the turntable and extend radially with respect to the center axis O of the turntable 5. The curved section 2 is included in a sector 6, having a central angle α . The value of the angle α is determined by the curved connecting section 2, the length and curvature of which are again determined by the position of the fixed track connections with which the turntable is to cooperate.

The most widely used turntable switch is that shown in FIG. 2, in which four track connections 10, 11, 12, 13 terminate, uniformly distributed, at the circumference of a circle, which is, simultaneously, the circumference of the turntable 5. The connection 11, as schematically indicated by the arrow, is opposite connection 10. The turntable switch, as specifically shown in FIGS. 1 and 2, permits flexible and universal interconnection between any one of the fixed tracks 10-13. The turntable 5, as described in FIG. 1, has a straight section 1, and a curved section 2. The curved connecting section 2 is located within the sector 6. The sector 6 in FIG. 2 has a central angle of $\pi/2$; the ends of the two segments 4 of the curved track section 2 terminate in the radii, defined by the ends of the segment 6.

The general construction required of a turntable switch, with a turntable 5 and two connecting sections 1, 2, is seen in FIG. 1. A straight line g passes through the center of the turntable 5, aligned with the straight section 1. A line g' can be drawn parallel thereto, spaced by a distance a from line g . A second parallel line g'' is drawn parallel to line g , spaced therefrom by the distance r .

The segment defined by the terminal or limit radii of segment a is extended to form line h . Parallel to line h , a line h' is drawn, spaced from line h by the distance r . At the intersection of lines h' and g'' , the center M of the radius of curvature of the two circular segments 4 will be obtained. The intersection of a perpendicular line to line h' passing through point M is a point at the circumference of the turntable 5, and this perpendicular line is tangent thereto. The distance r is the desired radius of curvature of the segments 4, for example the minimum radius of curvature for the particular track transport system under consideration.

Circular segment 4 terminates in radial direction at the circumference of the turntable 5. FIG. 2 clearly illustrates the relationship which is determined, on the one hand, by the straight portion 3, of dimension b of

the curved section 2, and the diameter D of the turntable 5, if the values a and r are given:

$$b = 2 \left(a - r \tan \frac{\pi}{8} \right) \quad (1)$$

$$D = 2 \left(\sqrt{2a + r \tan \frac{\pi}{8}} \right) \quad (2)$$

Equating

$$\tan \frac{\pi}{8} = \sqrt{2 - 1} \quad (3)$$

the relationships (1) and (2) become

$$b = 2a - 2r(\sqrt{2} - 1) \text{ and} \quad (4)$$

$$D = 2 \sqrt{2a + 2r(\sqrt{2} - 1)} \quad (5)$$

Equation (5) shows that as a or/and r increases, D also increases. To permit use of a straight portion 3, the following relationship must necessarily obtain, derived from equation (4):

$$\frac{a}{r} > \sqrt{2 - 1} \quad (6)$$

If four symmetrically located track ends 10-13 are used, the equations become very simple. They may, however, be similarly formulated for other angles α . To be able to use a straight portion 3, the inequality (6) must be met. The specific radii r, used in actual practice, may be small. Usually, therefore, any turntable will satisfy the inequality (6).

The turntable 5 need not be a circular disk; it may, also, be a truss or other girder construction, in which the connecting sections 1, 2 are suitably arranged. If such a construction is used, the circumference of the turntable 5 should be considered as an imaginary circle, on which the track sections 1, 2 terminate, in radial direction.

I claim:

1. Rotary turntable switch for transport systems hav-

ing first rail ends terminating in diametrical alignment, and other rail ends terminating at angles with respect thereto, comprising a straight connecting section (1) and a curved connecting section (2), wherein the curved connecting section (2) is characterized by

two circular segments (4), each terminating at one end adjacent the edge of the circle of rotation of the turntable switch, curved in the same direction, and a straight connecting portion (3) parallel to the straight connecting section (1) connected between the other ends of the circular segments and connecting the circular segments (4).

2. Switch according to claim 1, wherein the straight connecting section (1) passes through the center (O) of the turntable; and wherein the curved segments (4) have equal arc length, and equal radius of curvature (r), and terminate in radial direction at the edge of the circle of rotation of the turntable switch.

3. Switch according to claim 2, for two right-angle track sections, wherein the minimum diameter of the turntable (5) is defined by length D:

$$D = 2 \sqrt{2a + 2r(\sqrt{2} - 1)} \quad (a)$$

the straight connecting portion (3) is defined by length b:

$$b = 2a - 2r(\sqrt{2} - 1) \quad (b)$$

and the relationship of

$$\frac{a}{r} > \sqrt{2 - 1} \quad (c)$$

is satisfied, and wherein

a is the minimum distance between the straight connecting section (1) and the straight connecting portion (3);

r is the radius of curvature of the circular segments (4).
